(57) CLAIM

The ornamental design for footwear, as shown and described.

DESCRIPTION

FIG. 1 is a front perspective view of a shoe showing my footwear design;

FIG. 2 is a left side view thereof;

FIG. 3 is a right side view thereof;

FIG. 4 is a front view thereof;

FIG. 5 is a rear view thereof; and,

FIG. 6 is a top view thereof.

The broken line showing of the heel, heel cap, sole, buckles, buckle holes, portions of the straps, footbed, portion of the heel cup, portion of the shoe upper, and elastic portion is for illustrative purposes only and forms no part of the claimed design.

1 Claim, 6 Drawing Sheets
